UNITED STATES PATENT OFFICE.

JOHN HENRY WEST, OF BAYSWATER, LONDON, ARTHUR JAQUES, OF WATERLOO, AND CORNELIUS BRITTIFFE TULLY, OF NEWARK-ON-TRENT, ENGLAND.

PROCESS OF MANUFACTURING HYDROGEN OR GASES RICH IN HYDROGEN.

Application filed January 10, 1923. Serial No. 611,733.

To all whom it may concern:

Be it known that we, JOHN HENRY WEST, ARTHUR JAQUES, and CORNELIUS BRITTIFFE TULLY, all subjects of the King of Great Britain, residing, respectively, at Bayswater, in the county of London, England, Waterloo, in the county of Lancaster, England, and Newark-on-Trent, in the county of Nottingham, England, have invented certain new and useful Processes of Manufacturing Hydrogen or Gases Rich in Hydrogen, of which the following is a specification.

This invention relates to the manufacture of hydrogen or gases rich in hydrogen by the complete gasification of fuels containing a relatively high percentage of volatile constituents, such for example as bituminous coal, as opposed to fuels of the type of anthracite and coke which contain a relatively low percentage of volatile matter.

Amongst the various methods that have been proposed for obtaining hydrogen or gases containing a relatively high proportion of hydrogen from fuel or from fuel and steam are the following:—

(a) Ordinary coal gas, obtained by the carbonization of coal in closed retorts, contains part of the hydrogen originally present in the coal, this being no doubt set free by the partial cracking of the hydrocarbons, and methods are known for setting free practically the whole of the hydrogen present in the coal by cracking the hydrocarbons completely by passing them through a bed of incandescent coke or highly heated refractory material. Many coals contain about 5 per cent by weight of hydrogen, which corresponds to about 21,000 cubic feet of hydrogen at 15° C. and atmospheric pressure per ton of coal.

(b) The production of a mixture of roughly equal volumes of hydrogen and carbon monoxide, known as blue water gas, by acting with steam on the incandescent coke resulting from the carbonization of coal in retorts or coke ovens is also well known. In this case part of the coke has to be burnt in order to raise the remainder to a high temperature and to provide the large amount of heat absorbed in the water gas reaction $C + H_2O = CO + H_2$. One ton of average good coal will yield about 1500 lbs. of coke, of which about 500 lbs. will

have to be burnt for supplying the necessary heat for the purposes previously referred to, so that the production of hydrogen by the water gas reaction from the coke yielded by one ton of coal will theoretically be about 15,000 cubic feet. 60

(c) Various arrangements for the cracking of the hydrocarbons referred to in (a) in the presence of steam so as to avoid the deposition of carbon from the cracked hydrocarbons by causing the water gas reaction to take place between this carbon and the steam. 65

(d) Various methods for carrying out a reaction between the carbon monoxide in the gas obtained by methods (a) and (b) principally the latter method (b), and steam, according to the equation $CO + H_2O = CO_2 + H_2$, catalysts often being used to increase the speed of the reaction. 70 In this way a further quantity of hydrogen can be produced, which, supposing the reaction could be carried to completion, would amount to about 28,000 cubic feet per ton of original coal. 75

Further in order to avoid the loss of heat and fuel incurred in cases where coal is carbonized in one vessel and the resulting coke is withdrawn into the air and quenched by water, various methods have been proposed for the complete gasification of coal in one vessel or apparatus, that is to say, by carbonizing the coal in the upper part of the apparatus, and allowing the resulting coke to fall or pass directly, while still hot, 80 into the lower part of the apparatus where the water gas reaction takes place on steam being blown in. 85

The present invention has for its object the production of hydrogen by the aid of a complete or self-contained apparatus in one or other of the component parts of which there are utilized the various methods of obtaining hydrogen referred to in (a), (b), (c) and (d) above, and, as will be seen from what follows hereinafter, it comprises a particular method for the complete gasification of the fuel employed in the process so as to produce a mixture of gases consisting mainly of hydrogen and carbon monoxide and some carbon dioxide and the conversion of the carbon monoxide in the gases resulting from the complete gasification by the aid of steam and in the presence of a catalyst to carbon dioxide and hydrogen. 95 100 105 110

It is to be understood that the term complete gasification, as used in connection with the process of the present invention, is employed as designating a process in which 5 the resultant products consist practically wholly of what are usually termed permanent (i. e. non-condensable) gases and ash alone, the tarry vapors and hydrocarbons produced during the carbonization of 10 the coal becoming decomposed, as completely as possible, into hydrogen and carbon (which latter becomes available for the water gas reaction as well as the so-called fixed carbon of the coal) as hereinafter described.

According to a process for the production of a gas rich in hydrogen recently invented by one of the present applicants and embodied in application Serial No. 591,824, 20 filed October 2, 1922, fuel such as bituminous coal, containing a relatively large percentage of volatile constituents, as compared with fuel, such as anthracite or coke, which contains only a relatively low percentage of 25 volatile hydrocarbons, is distilled in an externally heated jacketed retort arranged above a lower fuel chamber into which the fuel which has been carbonized in the retort descends and wherein, after being raised to 30 a state of incandescence, by blowing it with air, it is converted, by injection of steam, into water gas which is allowed to mix with the gases produced by the distillation of the coal, the hydrocarbons whether condensable or non-condensable present in the latter gases being cracked or split up as completely as possible during the passage of the said gases through part or the whole, as the case may be, of the fuel bed in the 35 lower fuel chamber and through the jacket surrounding the retort, so that a mixture of water gas and permanent gases is thus obtained. This mixture of gases consists largely of hydrogen and carbon monoxide together with some carbon dioxide.

Throughout the present specification and claims the expression "intermittent mixed gas generator" is used to designate gas generating apparatus constructed and operating 50 in the manner just described.

According to the present invention the process for the production of hydrogen or gases rich in hydrogen consists in effecting the complete gasification of coal by means 55 of an intermittent mixed gas generator, taking off from the generator the hot mixture of gases resulting from the complete gasification, which consist largely of hydrogen, and carbon monoxide with some carbon dioxide, and subjecting the said mixture of gases whilst still in the heated condition and without any intermediate cooling to treatment with steam in the presence of a catalyst in a carbon monoxide converter so as to effect replacement of the carbon mon-

oxide in the gases by carbon dioxide and hydrogen.

On removal of the carbon dioxide from the gases after their treatment in the carbon monoxide converter, the remaining gas consists to a large extent of hydrogen, the actual proportion of hydrogen depending however on the extent to which the reaction of carbon monoxide to carbon dioxide in the converter is allowed to proceed, this extent 70 being determined by considerations which will hereinafter be referred to.

In order that the invention may be clearly understood and readily carried into effect 80 the same will now be described more fully with reference to the accompanying drawings, in which:—

Figure 1 shows the intermittent mixed gas generator in vertical section with the carbon monoxide converter and the connections 85 thereto diagrammatically indicated, and

Figures 2, 3 and 4 are horizontal sections on the lines 1—1, 2—2, and 3—3 respectively of the generator shown in Figure 1.

The intermittent mixed gas generator comprises an upper retort portion A, which may be of truncated conical shape into which the coal is fed at the top through a suitable valve of cone or sliding type, and a lower chamber C constituting the gas producer. 90 Surrounding the retort A and serving to heat it is a jacket B charged with chequer-work and surmounted by an equalizing chamber D, the jacket being heated to the desired high temperature by passing through it the producer gas obtained by blowing air through the mass of carbonized fuel in the lower chamber C, together with a secondary supply of air to insure complete combustion of any combustible gases within the jacket 95 as hereinafter described. The gases of combustion or "blow" gases pass through the equalizing chamber D at the top of the chequer-work, after which they are discharged into the atmosphere after their 100 sensible heat has been removed as effectively as possible by utilizing it for example for raising part of the steam required or for preheating the air for blowing the producer. 105 Alternatively part or all of the blow gases 110 may be used for maintaining the carbon monoxide converter K at the desired temperature as hereinafter described. The coal passes slowly down through the retort, whilst being heated by the hot gases travelling up through the jacket B of the apparatus, and is thereby carbonized, the resulting carbonized coal falling direct into the producer C. After the carbonized fuel in the producer C has been raised to a high 115 state of incandescence by blowing air through it, (the air inlet at the base of the producer chamber being indicated at E), the air supply is cut off and steam forced 120 into the incandescent fuel, the water gas 125 produced being taken off through the pipe 130

thereby obtained being passed through openings or nostrils F at the base of the retort and thence into and through the highly heated jacket B of the retort, the gas evolved 5 from the heated coal in the retort being also simultaneously caused to pass through the nostrils and into and through the jacket B, a mixture of gases consisting largely of hydrogen and carbon monoxide, together 10 with some carbon dioxide, being thus obtained. The gas evolved from the coal during its distillation on its way to the nostrils F has to pass downwards through the high temperature zone at the lower part of 15 the retort and the top of the incandescent fuel in the lower fuel chamber, whereby tar and volatile hydrocarbons contained in the said gas are partly cracked or split up, and the resulting gases together with the 20 water gas produced during the "make" pass together through the nostrils F and into the jacket B. Volatile hydrocarbons which have escaped cracking or splitting up in the high temperature zone referred to will be cracked 25 or split up in the jacket B of the retort by contact with the previously heated chequer-work therein. On leaving the upper part of the chequer-work the gases pass through the equalizing chamber D and thence through 30 the outlet R and pipes S, T and U to the carbon monoxide converter K as hereinafter described. A secondary supply of air is admitted to the lower end of the jacket B of the retort through the inlet G, whence it 35 passes round the annular duct L and through the ports M to a combustion chamber H below the jacket B and in communication therewith and with the nostrils F, so as to insure complete combustion within the 40 jacket or combustion chamber of any combustible gas contained in the producer gas generated during the "blow" thereby enabling the heat resulting from such combustion to be utilized in raising the temperature 45 of the jacket or combustion chamber and jacket and thereby assisting in the cracking or splitting up of hydrocarbons passing into the jacket or combustion chamber and jacket from the retort. To prevent deposition of 50 carbon in the jacket or combustion chamber and jacket by cracking or splitting up of hydrocarbons therein, steam may be admitted thereto during the "make" to form water gas by interaction with the liberated 55 carbon. In order to equalize the heating of the bed of fuel in the lower chamber C of the intermittent mixed gas generator and to avoid excessive cooling of the lower part of such bed near the grate, during a portion 60 of the "make" period the flow of steam and coal gas may be reversed, that is to say, steam may be admitted either at the top of the jacket B or to the equalizing chamber D if used, or into the combustion chamber H 65 at the base of the jacket. In this case the gases containing the volatile hydrocarbons issuing from the retort pass downwards with the steam through the entire bed of incandescent fuel in the lower fuel chamber and are therein cracked or split up, the resulting 70 mixed gases being led away from the space beneath the grate through the outlet J and pipes J¹, J¹¹, T and U to the carbon monoxide converter K. Suitable pipe connections with valves are provided to enable 75 this action to be effected. If desired a cycle of working may consist of a "blow" period followed by a period of steaming upwards only, or of alternate steaming upwards and downwards, and the working may consist 80 in any convenient sequence of such cycles.

In the working of such an intermittent mixed gas generator the heat of the blow gases leaving the generator may advantageously be used for generating the steam or 85 some of it required in carrying out the process, or for preheating the air used during the "blow" period, or for maintaining the carbon monoxide converter at the desired temperature or partly for each of these purposes. The heating of the coal in the retort may also be effected partly by introducing a regulated quantity of air into the retort itself so as to cause combustion of part of 90 the coal therein. Also to increase the percentage of hydrogen in the mixed gas eventually leaving the intermittent mixed gas generator, liquid or semi-liquid fuel rich in hydrogen, such as fuel oil, crude petroleum and the like may be introduced into the retort. With an intermittent mixed gas generator of the kind in question there may advantageously be used valve apparatus of 95 the kind described in the specification of British Patent No. 112091, and the admission of steam to the generator and the operation of the said valve apparatus may advantageously be effected and controlled by apparatus of the kind described in the specification of British Patent No. 159409. 100

Whilst in the manufacture of gas for heating or illuminating purposes it is not desirable to crack or split up such substances as methane, in the case of the present invention it is desirable that all hydrocarbons 105 should be split up into hydrogen and carbon, the latter being available for the reaction with steam to form water-gas. In order to insure this complete or substantially complete cracking of the volatile hydrocarbons present in the products of distillation of the coal in the retort, it is important that the fuel in the lower fuel chamber, and the chequer-work in the jacket of the retort, should 110 be maintained at such a high temperature 115 that the water gas reaction within the lower fuel chamber cannot be carried out mainly according to the equation $C + 2H_2O = CO_2 + 2H_2$, which necessitates the use of a comparatively low temperature. It is there- 120

125

130

fore preferred to carry out the water gas reaction within the lower fuel chamber principally according to the equation $C + H_2O = CO + H_2$, although the reaction to carbon dioxide may be used as far as is compatible with the maintenance of a sufficiently high temperature to insure the cracking and gasification of substantially the whole of the volatile hydrocarbons evolved from the coal.

10 By working the generator in this way the "make" gases will leave it at a high temperature, say $1000^{\circ} C.$ to $1100^{\circ} C.$, so that, after mixing with steam, the gas and steam mixture can be obtained at a suitable temperature for treatment in the converter as described below.

15 In order to effect the conversion of the carbon monoxide, the gases issuing from the intermittent mixed gas generator during the "make" period are passed into the carbon monoxide converter K wherein they are subjected at a comparatively low temperature to the action of additional steam in such manner that a considerable proportion of the carbon monoxide in the gas will be converted into carbon dioxide with the production of further hydrogen according to the equation $CO + H_2O = CO_2 + H_2$. Since this reaction is exothermic little or no heat need be supplied to the converter except to compensate for radiation losses. The converter K may be filled with chequer-work or with pieces of refractory material presenting a large surface for promoting catalytically the desired reaction, or preferably it may contain suitable catalyst material supported for instance on perforated trays superimposed one above the other. In certain cases part of the converter vessel may contain chequer-work and another part trays of catalyst material or two converter vessels may be used one of which may contain chequer-work and another trays of catalyst material. At the commencement of operations in order to raise the converter to the desired high temperature, gas from the generator or from another source may be burnt therein, the said gas passing around the retorts in the converter containing the catalyst material. When the desired temperature of the converter has been reached, the supply of heating gas is cut off, blow gases admitted through the pipe V being substituted. The converter is so constructed that the blow gases passed therethrough and the products of combustion of the gas used for heating it up as described above, in order to avoid any detrimental effect on the catalyst material do not come into direct contact therewith. After passing through the converter the blow gases escape by the pipe W. Should the heat of the blow gases be insufficient to maintain the desired temperature in the converter, a small quantity of air may be blown into the top part of the converter and there be

burnt with a portion of the hydrogen and carbon monoxide of the gas under treatment. In working the carbon monoxide converter it is preferred to pass the gas and steam into it in a downward direction and to add a portion only of the total steam required at the top of the apparatus. The temperature of the steam used should be such that the temperature of the mixture of gas and steam at the top of the apparatus should be between about $600^{\circ} C.$ and $800^{\circ} C.$ and preferably about $700^{\circ} C.$ The mixed gases from the generator produced during the "make" enter the top of the converter through the pipe U, passing in the direction R, S, T, U, or J, J', J'', T, U, according as the steaming is taking place in the upward or downward direction, and after passing, together with the additional steam admitted, over the catalyst material finally leave the converter by the pipe Y, hence passing through the washbox X and to scrubbers and gas holders whereupon they may be treated as subsequently described. As indicated in Figure 1, part of the total additional steam required for effecting the reaction in the converter is admitted at the top of the apparatus through the pipes Z, while the remainder of the steam is preferably introduced at several points on the way down the converter (as for example through the pipes Z' and Z'') so as not only to neutralize the rise in temperature due to the heat of the reaction but to produce a gradual decline in temperature from the top of the converter to the bottom thereof where the temperature should be between $400^{\circ} C.$ and $550^{\circ} C.$ and preferably may be at about $400^{\circ} C.$ The precise temperatures to be employed depend upon the particular catalyst which is used. The degree to which the reaction should be carried in the carbon monoxide converter, subject of course to the limit which is practically obtainable, may be varied to suit circumstances, particularly with regard to the arrangements to be used for raising and superheating the steam, and it may be, the purposes for which the resulting gas is to be used.

The treated gas leaving the carbon monoxide converter is passed through a condenser to remove the excess steam or it may be passed through a boiler, heat interchanger, or the like, in order to utilize the latent heat of excess steam and also the sensible heat of the gases. The cooled gas, which will now consist almost entirely of hydrogen and carbon dioxide together with comparatively quite small quantities of carbon monoxide and nitrogen, is subsequently treated in a known and suitable way for the separation, as far as possible or desirable of the hydrogen from the other constituents of the gas.

To remove the carbon dioxide the gas

- may conveniently be washed in an absorption tower or towers with water, preferably under pressure and with or without the addition of lime water, ammonia, or the like, 5 in order to remove the last portions of carbon dioxide, the flow of water or solution being counter-current to that of the gas. After this treatment, the gas, if necessary, can be further treated for the separation 10 of the hydrogen therein from the other constituents present, as for instance by liquefaction. When carrying out the conversion process so that very little carbon remains in the gas leaving the converter, separation of the hydrogen from the other constituents of the gas by liquefaction may be unnecessary and might for instance be replaced, so far as removal of carbon monoxide is concerned, by the known method 15 of causing the latter to react with hydrogen in presence of a catalyst producing methane and water.

From the foregoing description, it will be seen that the apparatus used in carrying out the invention comprises essentially an intermittent mixed gas generator operatively combined with a carbon monoxide converter and may conveniently be followed by an absorption apparatus, for the removal 20 of carbon dioxide, these being in communication with each other and acting in conjunction with each other.

In carrying out the present invention the fuel used is coal or other bituminous fuel 25 containing as high a percentage of hydrogen as possible and as before mentioned the hydrocarbons obtained by gasification of the coal are cracked or split up, as completely as possible, into hydrogen and carbon, which latter is available for the water gas reaction as well as the so-called fixed carbon of the coal, so that the products of the process consist practically entirely of non-condensable gases and ashes, whilst the 30 carbon monoxide produced in the first stages of the process is converted to a large extent by steam into carbon dioxide, setting free the hydrogen in this steam, and thus producing as a final result substantially more hydrogen per ton of coal than is obtained by any of the processes hitherto known.

What we claim and desire to secure by Letters Patent of the United States is:—

1. A process for the production of hydrogen or gases rich in hydrogen which consists in completely gasifying coal in an intermittent mixed gas generator, taking off from the generator the hot mixture of gases resulting from the complete gasification, the 45 said gases consisting largely of hydrogen and carbon monoxide with some carbon dioxide, subjecting the said mixture of gases while still in the heated condition and without any intermediate cooling to treatment with steam in the presence of a catalyst in 50 a carbon monoxide converter and maintaining a gradual fall of temperature between the two ends of the said converter by introducing a portion of the required amount of steam 55 at or near that end of the converter 70 at which the hot mixture of gases from the generator is admitted and the remainder of the steam required at a plurality of points between the two ends of the converter.
2. A process for the production of hydrogen or gases rich in hydrogen which consists in completely gasifying coal in an intermittent mixed gas generator, taking off from the generator the hot mixture of gases resulting from the complete gasification, the 60 said gases consisting largely of hydrogen and carbon monoxide with some carbon dioxide, subjecting the said mixture of gases while still in the heated condition and without any intermediate cooling to treatment 65 with steam in the presence of a catalyst in a carbon monoxide converter and maintaining a gradual fall of temperature between the two ends of the said converter by introducing a portion of the required amount of steam 70 at or near that end of the converter 75 at which the hot mixture of gases from the generator is admitted and the remainder of the steam required at a plurality of points between the two ends of the converter.
3. A process for the production of hydrogen or gases rich in hydrogen which consists in completely gasifying coal in an intermittent mixed gas generator, taking off from the generator the hot mixture of gases resulting from the complete gasification, the 80 said gases consisting largely of hydrogen and carbon monoxide with some carbon dioxide, subjecting the said mixture of gases while still in the heated condition and without any intermediate cooling to treatment 85 with steam in the presence of a catalyst in a carbon monoxide converter and maintaining a gradual fall of temperature between the two ends of the said converter by introducing a portion of the required amount of steam 90 at or near that end of the converter 95 at which the hot mixture of gases from the generator is admitted and the remainder of the steam required at a plurality of points between the two ends of the converter, and effecting the operation of the intermittent mixed gas generator in such manner that the mixture of gases consisting largely of hydrogen and carbon monoxide with some carbon dioxide leaving the 100 generator is at a temperature substantially high enough to insure that, after the addition of steam thereto, the resulting gas steam mixture will be at the desired temperature for treatment in the converter.
4. A process for the production of hydrogen or gases rich in hydrogen which consists in completely gasifying coal in an intermittent mixed gas generator, taking off from the generator the hot mixture of gases resulting from the complete gasification, the 105 said gases consisting largely of hydrogen and carbon monoxide with some carbon dioxide, subjecting the said mixture of gases while still in the heated condition and without any intermediate cooling to treatment 110 with steam in the presence of a catalyst in a carbon monoxide converter so as to effect replacement of the carbon monoxide in the 115 gases by carbon dioxide and hydrogen, passing hot blow gases from the intermittent mixed gas generator through the said converter but in indirect contact with the catalyst material therein so as to maintain the carbon monoxide converter at the desired temperature for the reaction of the mixed gases with steam, and maintaining a gradual fall of temperature between the two ends of the said converter by introducing a portion of the required amount of steam 120
5. A process for the production of hydrogen or gases rich in hydrogen which consists in completely gasifying coal in an intermittent mixed gas generator, taking off from the generator the hot mixture of gases resulting from the complete gasification, the 125 said gases consisting largely of hydrogen and carbon monoxide with some carbon dioxide, subjecting the said mixture of gases while still in the heated condition and without any intermediate cooling to treatment with steam in the presence of a catalyst in a carbon monoxide converter at the desired temperature for the reaction of the mixed gases with steam, and maintaining a gradual fall of temperature between the two ends of the said converter by introducing a portion of the required amount of steam 130

at or near that end of the converter at which the hot mixture of gases from the generator is admitted and the remainder of the steam required at a plurality of points 5 between the two ends of the converter.

4. A process for the production of hydrogen or gases rich in hydrogen which consists in completely gasifying coal in an intermittent mixed gas generator, taking off 10 from the generator the hot mixture of gases resulting from the complete gasification, the said gases consisting largely of hydrogen and carbon monoxide with some carbon dioxide, subjecting the said mixture of gases 15 while still in the heated condition and without any intermediate cooling to treatment with steam in the presence of a catalyst in a carbon monoxide converter so as to effect replacement of the carbon monoxide in the 20 gases by carbon dioxide and hydrogen, and maintaining the temperature of the gases at that end at which the gases enter the carbon monoxide converter at about 600° C. to 800° C. and the temperature of the gases 25 at that end at which the gases leave the converter at about 400° C. to 550° C.

5. A process for the production of hydrogen or gases rich in hydrogen which consists in completely gasifying coal in an intermittent mixed gas generator, taking off 30 from the generator the hot mixture of gases resulting from the complete gasification, the said gases consisting largely of hydrogen

and carbon monoxide with some carbon dioxide, subjecting the said mixture of gases 35 while still in the heated condition and without any intermediate cooling to treatment with steam in the presence of a catalyst in a carbon monoxide converter so as to effect replacement of the carbon monoxide in the 40 gases by carbon dioxide and hydrogen, maintaining the carbon monoxide converter at the desired temperature for the reaction of the mixed gases with steam by passing hot blow gases from the intermittent mixed 45 gas generator through the said converter but in indirect contact with the catalyst material therein, and maintaining a gradual fall of temperature between the two ends of the said converter by introducing a portion 50 of the required amount of steam at or near that end of the converter at which the hot mixture of gases from the generator is admitted and the remainder of the steam required at a plurality of points between 55 the two ends of the converter, the temperature of the gases at the hotter end of the carbon monoxide converter being maintained at about 600° C. to 800° C. and the temperature of the gases at the cooler end 60 of the converter being maintained at about 400° C. to 550° C.
